(57) **CLAIM**

The ornamental design for a photoelectric sensor, as shown and described.

DESCRIPTION

FIG. 1 is a front elevational view of the photoelectric sensor;
FIG. 2 is a rear elevational view thereof;
FIG. 3 is a left-side elevational view thereof;
FIG. 4 is a right-side elevational view thereof;
FIG. 5 is a top plan view thereof;
FIG. 6 is a bottom plan view thereof; and,
FIG. 7 is a front, right-side, top perspective view thereof.
The broken lines depict environmental subject matter only
and form no part of the claimed design. The material that
would otherwise be visible through the transparent portion is
not claimed, and thus not shown.
